GRILLE MATERIAL

Millard Fillmore Harty, Jr., Mount Clemens, Mich., assignor to The Harrington & King Perforating Co., Chicago, Ill., a corporation of Illinois

Application January 2, 1958, Serial No. 49,114

Term of patent 14 years

(Cl. D54—2)

Fig. 1 is a plan view of a representative portion of a grille material showing my new design, the balance of the material being like that shown;

Fig. 2 is a cross-sectional view taken at the line 2—2 of Fig. 1 and shown in enlarged scale; and

Fig. 3 is a cross-sectional view taken at the line 3—3 of Fig. 1 and shown in enlarged scale.

I claim:

The ornamental design for a grille material, substantially as shown and described.
